UNITED STATES PATENT OFFICE.

JOHN L. SIGNORETTE, OF LOS ANGELES, CALIFORNIA.

ORE-CONCENTRATOR.

1,098,183.

Specification of Letters Patent.

Patented May 26, 1914.

Application filed May 9, 1912. Serial No. 696,208.

To all whom it may concern:

Be it known that I, JOHN L. SIGNORETTE, a citizen of the United States, residing at Los Angeles, in the county of Los Angeles, 5 State of California, have invented certain new and useful Improvements in Ore-Concentrators; and I do hereby declare the following to be a full, clear, and exact description of the invention, such as will enable 10 others skilled in the art to which it appertains to make and use the same.

This invention relates to improvements in ore concentrators.

The principal object of the invention is 15 to provide a device of this character including novel means for operating a shaking tray, in which the pulp is poured, to insure the proper settling of the precious values.

Another object is to provide a novel means 20 for operating an outlet valve to automatically draw off the settling.

A further object is to provide a novel means agitating the pulp in the tray, so 25 that the precious values contained therein are separated therefrom and forced to settle to the bottom of the tray.

These and other objects will be apparent 30 from the following description and with particular reference to the accompanying drawings.

In the drawings: Figure 1 is a side elevation of my device, Fig. 2 is a top plan view thereof, Fig. 3 is an end elevation, Fig. 4 is a vertical section on the line 4—4 of Fig. 2, 35 and Fig. 5 is a section on the line 5—5 of Fig. 2.

Referring particularly to the drawings, 10 represents the base, on one end of which are formed vertical uprights 11, 12 and 13 40 respectively. The base is provided with intermediate transversely extending supporting strips 14 and 15, on which are secured the blocks 16, there being four of these blocks. A longitudinally convexed tray 17 45 is disposed above the base, and has secured to its bottom the blocks 18, provided with the recesses 19, to receive the upper ends of the flattened spring supporting legs 20, the lower ends of said legs being secured to 50 the before-mentioned blocks 16. The spring legs 20 are so arranged that the tray will vibrate or reciprocate longitudinally. At a point directly opposite the upright 11, on the other side of the base, is a similar up- 55 right 21, and in each one of these uprights is mounted an adjustable bolt 22, adjustable

therethrough by means of the adjusting nut 23, each of said bolts having a metal bumper head 24 on its inner end, for a purpose to be referred to later. Secured to the bottom of 60 the tray and running longitudinally thereof is a bumper bar 25, formed preferably of wood, and having the protecting metallic band 26 around the ends thereof, the ends of 65 said bar being so disposed as to bump against the heads 24, when the tray vibrates or reciprocates longitudinally, thereby suddenly checking and jarring the tray at each limit of its movement, and securing the shaking up of the pulp within the tray and the effective settling of the precious values. 70

On the uprights 12 and 13 are the bearing blocks 27 and 28, in which blocks, is journaled a driving shaft 29. On one end of this shaft is mounted a slotted crank disk 30, 75 and near the other end a tight pulley 31 and an idle pulley 32. On the disk 30 is a wrist pin 33, to which is connected one end of a connecting rod 34, the length of the stroke of the rod being regulated by means of the 80 slotted disk 30. The opposite end of the connecting rod is threaded as at 35, and passes through a perforated lug 36 secured to the bottom of the tray, and on each side of the said lug are the adjusting nuts 37. 85 On each side of the lug 36 and between the said lug and between each of the nuts 37 is a coil spring encircling the curved portion of the rod 34, the purpose of which will appear later. 90

In one of the vertical edges of the tray is a cutaway portion 39, which forms an overflow for the tray, said cutaway portion being slightly offset as indicated at 40. At one side of the tray is arranged the end of a 95 sluice 41 from which the pulp is fed to the tray. Extending longitudinally over the tray and secured at its ends to the uprights 11 and 21 respectively, is a bar 42, having a series of downwardly projecting fingers 43, 100 the said fingers extending into the tray. Secured to this bar is a rectangular frame, the longitudinal members 44 of which are similarly provided with fingers 45, and also extending into the tray. This frame and the 105 bar 41 are held stationary, while the tray reciprocates therebeneath, the fingers 43 and 45 agitating the pulp within the tray, and forcing any small particles of precious metal to separate from the pulp and sink to the 110 bottom. In the center of the offset portion 40 is a sight opening 46, closed by means of

the glass plate 47, for the purpose of viewing the interior of the tray when it is desired to inspect the contents of the same, so that the valve 56 may be opened at the proper time.

5 In the bottom of the tray near the opening 46 is an outlet opening for the settling, and secured to the bottom of the tray is an apertured plate 49, the opening of which registers with the opening 48 in the tray. Pivoted on the bottom of the tray at the point 50 is an outwardly projecting lever or arm 51, having the curved portion 52 disposed directly beneath the plate 49 and provided with a boss 53, said boss having a rectangular opening 54 for the reception of the rectangular stem 55 of a valve 56, said valve being of the plate type, and engaging tightly over the aperture of the plate 49, a spring 57 being disposed between the valve and the 20 boss for holding said valve tightly against the plate 49. Secured to the offset side of the tray is a depending yoke-shaped guiding hanger 58, which supports the outer portion of the arm 51. Secured to the uprights 11 25 and 21 and extending therebetween is a yoke-shaped bar 59, having a flattened central portion 60, provided with a series of openings 61, for the reception of a pair of stop plugs 62, said flattened portion of the 30 bar being disposed directly beneath the outer end of the arm 51. By inserting the plugs 62 in the openings on opposite sides of the arm 51, said arm will engage with the plugs alternately, as the tray reaches the limit of 35 its movement in either direction, so that said arm 51 is moved first one direction then the other to slide the valve 56, to cover and open the outlet opening 48.

40 In the operation of the device, power is applied to the shaft 29 through the medium of the pulley 31, which rotates the crank disk 30 and causes the connecting rod 34 to impart a reciprocating movement longitudinally of the tray. As the tray reaches each 45 limit of its reciprocating movement the bumper bar 25 engages with one of the heads 24, and is given a sudden jar which will shake up or agitate the contents of the tray, to separate the finer particles of precious metal and cause them to be precipitated to the bottom. As the tray is jarred at each end of its movement by the bumper bar 25 striking the heads 24, the shock is taken up by the springs 38, so that a series 50 of smaller reciprocations or vibrations are imparted to the tray between the main or positive vibrations. Thus the tray is given a sudden jar at each end of its movement, and a series of shorter vibrations immedi-

ately succeeding each end bump. At the 60 same time the fingers 43 and 45 keep the pulp thoroughly agitated within the tray, so that during the operation of the device there are three distinct actions to cause the proper settling of the precious values to 65 the bottom of the tray, namely: the bump at each end of the movement of the tray, the series of short vibrations caused by the springs 39, and fingers 43 and 45.

Particular attention is called to the fact 70 that as the tray reciprocates the arm 51 is thrown in one direction or the other so that the valve will uncover the opening 48, and permit the settling of precious values to 75 pass out through the said opening, and by adjusting the plugs 62 in the various openings 61, the opening 48 may be uncovered to a greater or lesser extent. Furthermore, the shorter vibrations of the tray produced by means of the springs 38 occur at the instant 80 when the valve is closed or nearly closed, so that when the valve is opened, the settling resulting from said shaking will quickly pass out through the openings.

What is claimed is:

1. In an ore concentrator, the combination with a base, of resilient supports carried by said base, a tray mounted on the supports, a longitudinally extending bumper bar connected with the bottom of the tray, a standard mounted on the base adjacent each end of the tray, resilient means for reciprocating the tray, means carried by the standards adapted to be engaged by the bumper bar during the reciprocation of the tray to jar 95 such tray and independent adjusting devices for the resilient means and last mentioned means whereby the shock at either end of the reciprocation may be regulated.

2. In an ore concentrator, the combination 100 with a base, of a tray resiliently supported upon the base, resilient means for reciprocating the tray, said means including a lug connected to the tray, a bar passing through said lug, springs surrounding said bar on 105 each side of said lugs, nuts on the bar for adjusting the tension of the springs independently; a bumper bar connected with the tray, bumper heads engageable by the bumper bar, and means for independently 110 adjusting the position of said heads.

In testimony whereof, I affix my signature, in presence of two witnesses.

JOHN L. SIGNORETTE.
